UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

TYPOGRAPHICAL DISTRIBUTING MACHINE.

Application filed March 11, 1925. Serial No. 14,633.

To all whom it may concern:

Be it known that I, GEORGE P. KINGSBURY, a citizen of the United States, residing at Brooklyn, in the county of Kings and State of New York, have invented certain new and useful Improvements in Typographical Distributing Machines, of which the following is a specification.

This invention relates to typographical machines, such as linotype machines of the general organization represented in U. S. Letters Patent to O. Mergenthaler, No 436,532, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through a distributing mechanism to the magazine from which they started. In some machines, such as the commercial Model 9, where matrices may be drawn from several magazines and mixed together in the same line, the distributing mechanism includes a primary distributor which first sorts the matrices according to font, and a plurality of main distributors which thereafter sort the matrices of the individual fonts according to character and restore them to their proper channels in the magazines. With this type of distributing mechanism, the matrices, after font separation, pass down chutes or tubes and enter so-called lower distributor boxes, wherein they are guided upon inclined rails into engagement with reciprocating pawls or escapements, which feed them one at a time to the main distributors. In order that these pawls or escapements may cooperate properly with the matrices, the latter are provided in their bottom edges with central notches, which necessarily vary in shape and depth according to the thickness of the individual matrices. Besides adding to the cost of production, such notches in the matrices materially limit the space ordinarily required for the regular font notches and, moreover, seriously weaken the matrices, especially when the latter are formed with other necessary cuts or notches. Furthermore, matrices comprising fonts used on other ma-

chines, such as those of the single distributor class, are excluded from use on machines of the multiple distributor class described, since they do not have the required central notches.

The present invention is intended to obviate the foregoing difficulties and contemplates certain improvements whereby the distributing mechanism may receive and handle matrices of all fonts whether they have or have not the objectionable central notches referred to. To this end, each of the lower distributor boxes is provided with shoulders for arresting the matrices in advance of the distributor screws, and with a lifting finger to raise the arrested matrices successively above said shoulders and permit their escape by gravity into position to be picked up by the leading ends of the screw threads. In the preferred embodiment illustrated, the released matrices are directed to the pick-up position by short inclined guiding surfaces onto which each matrix in turn is pushed as it is raised by the lifting finger.

In the accompanying drawings, the invention has been shown merely in preferred form and by way of example and as applied to the specific type of distributing mechanism indicated. However, many changes and variations may be made therein and in its mode of application, which will still be comprised within its spirit. It is to be understood, therefore, that the invention is not limited to any specific form or embodiment except in so far as such limitations are specified in the claims.

In the drawings:

Fig. 1 is a side elevation of a lower distributor box, partly broken away, equipped with the present improvements;

Fig. 2 is a vertical, transverse section, taken on line 2-2 of Fig. 1;

Fig. 3 is an elevation, similar to Fig. 1 but showing a matrix lifted above the arresting shoulders; and

Fig. 4 is a detail view showing a modified construction.

The matrices X are released by the primary distributor (not shown) and enter one or another of the lower distributor boxes A, wherein they are guided and sustained by their projecting ears α upon upper and lower inclined rails A¹, A². Each

box is associated with a distributor, which comprises the usual longitudinally ribbed bar B and the set of matrix conveying screws B¹, the arrangement being such that, 5 as the matrices escape from the box to the pick-up position, they will be immediately advanced by the screws across the horizontal rail extensions A³ into engagement with the bar B and thence along the same until 10 finally released above their respective magazine channels. The foregoing parts and their mode of operation, except as hereinafter pointed out, are or may be of any approved construction or as embodied in the 15 commercial Model 9 linotype.

According to the present invention, each of the distributor boxes A is provided with an escapement mechanism for properly controlling the delivery of matrices, one at a 20 time, to the distributor screws, irrespective of the special notches hereinbefore mentioned. As shown in Fig. 1, matrices passing from the chute G are straightened up in the usual way at X¹, so as to properly 25 engage the upper and lower guide rails A¹, A², down which they slide by gravity until arrested in upright position by the engagement of their projecting ears α with shoulders A⁴ formed on the upper guide rails A¹ 30 and corresponding shoulders A⁵ formed on the lower guide rails A². A lifting finger C, mounted to reciprocate within the box and actuated through the usual connections from a cam or eccentric stud B⁴ on one of 35 the screws B, is employed to release the arrested matrices one at a time, by lifting them successively above the shoulders A⁴, A⁵. As the matrices are thus released, they slide down short inclined surfaces A⁶ 40 formed on the guide rails and which direct them into position to be picked up by the leading ends B² of the screw threads. As will be noted, the shoulders A⁴, A⁵ are disposed in a vertical plane lying slightly in 45 advance of the receiving ends of the distributor screws, so that a released matrix will have a comparatively short distance to travel in escaping to the pick-up position. The distributor screws may consequently be 50 readily and accurately timed to receive and advance the matrices as they escape from the distributor box. In this connection, it is pointed out that the screws are recessed or cut away at their receiving ends, as at 55 B³, to give a released matrix more room and time to reach the pick-up position before it is engaged by the screw-threads.

With the foregoing arrangement, the feeding of the matrices to the distributor screws might take place in the required manner if several matrices were stacked up in front of the arresting shoulders, since the weight of the succeeding matrices would tend to displace the foremost matrix face- 60 wise over the arresting shoulders when

raised by the lifting finger C. While an escapement of this kind might prove satisfactory under many conditions, it is proposed in carrying out the present invention to provide means for effecting the positive 70 facewise displacement of the elevated matrices in order to facilitate their escape and insure their delivery to the distributor screws. To this end, the distributor box A is further provided with a spring controlled 75 dog D, pivoted thereto as at D¹, and having a cross-piece D² arranged directly above an arrested matrix so as to be engaged by the upper ears thereof when it is elevated by the lifting finger C. Accordingly, as each 80 matrix is lifted above the arresting shoulders A⁴, A⁵, the lower portion D³ of the dog is caused to move forwardly against the body of the matrix and push it facewise over said shoulders above the inclined surfaces A⁶ (see Fig. 3); then, as the lifting finger recedes, the matrix slides by gravity 85 down the inclined surfaces into position to be picked up by the screws.

In order to guard against the possibility 90 of a matrix being pushed over too far by the dog D, there are provided (see Figs. 1 and 2) two pairs of fixed shoulders E¹, E², arranged in position to engage the four 95 projecting ears of a lifted matrix and arrest it in the desired plane as it is pushed forwardly by the dog. As shown, the shoulders E¹ of the upper pair are arranged to 100 cooperate with the upper ears of the matrix, being formed on overhanging fingers E secured to opposite sides of the box casing, while the shoulders E² of the lower pair are arranged to cooperate with the lower 105 projecting ears of said matrix, being formed by cutting away the lower edges of the upper guide rails A¹.

It will now be seen that, in the operation 110 of the parts, a matrix entering the box A will slide down the guide rails A¹, A² into contact with the arresting shoulders A⁴, A⁵ 115 and be lifted by the finger C into engagement with the dog D, which by such lifting action pushes the matrix facewise past the arresting shoulders and up against the restraining shoulders E¹, E², when, upon the descent of the lifting finger, the matrix is allowed to escape down the inclined surfaces A⁶ to the screw pick-up position.

In the present embodiment, the dog D 120 serves the additional purpose of preventing the raising by the lifting finger of more than one matrix at a time. That is to say, the lower portion D³ of the dog is made in the form of a blade to cooperate with the usual central separator slots, with which all 125 matrices above a minimum thickness are provided. The forward edge of the blade D³ is set at the required distance in advance of the matrix arresting shoulders by the engagement of the upper end D⁴ of the dog. 130

with a fixed part of the box casing (Fig. 1).

Fig. 4 shows a modification, according to which the lifted matrices are displaced forwardly over the arresting shoulders by cam surfaces A^7 , A^8 , in lieu of the vibratory dog D. These cam surfaces A^7 , A^8 are formed respectively in the lower edges of the upper guide rails A^1 and in plates B^5 secured to opposite sides of the box casing, and are so arranged as to engage the four projecting ears α of each matrix as it is lifted above the arresting shoulders A^4 , A^5 . Hence, a matrix arrested in the full line position Y will, as it is raised by the lifting finger C, be guided by the cam surfaces to the dotted line position Z and then escape down the inclined surfaces A^6 in the manner before described.

As before stated, the invention has been herein shown and described only in preferred form and by way of example, and it should be understood that it is susceptible of embodiment in other forms and arrangements without departing from its scope. One of the prominent features involved is the lifting of the matrices, one at a time, to effect their release and then allowing the released matrices to pass by gravity to the pick-up position of the screws. The use of inclined surfaces to direct the released matrices to the pick-up position is also important, although it is realized that the matrices may be caused to descend such surfaces other than by displacing the matrices facewise as they are lifted.

Having thus described my invention, its construction and mode of operation, what I claim and desire to secure by Letters Patent of the United States, is as follows:

1. In a typographical distributing mechanism comprising a distributor bar and a set of matrix conveying screws, the combination of guide means along which the matrices pass by gravity to the screws, said guide means being adapted to support a plurality of matrices in facewise contact, means for arresting the matrices at a point in advance of the screws, and a reciprocating finger for releasing the arrested matrices, one at a time, to permit their escape by gravity into position to be picked up by the screws.

2. In a typographical distributing mechanism comprising a distributor bar and a set of matrix conveying screws, the combination of guide means along which the matrices pass by gravity to the screws, means for arresting the matrices at a point in advance of but closely adjacent the screws, means for releasing the arrested matrices, one at a time, to permit their escape by gravity into position to be picked up by the screws, and inclined surfaces arranged to direct the released matrices to the pick-up position.

3. In a typographical distributing mechanism comprising a distributor bar and a set of matrix conveying screws, the combination of a distributor box through which the matrices pass by gravity, shoulders or abutments for arresting the matrices within the box, and a reciprocating finger for lifting the arrested matrices, one at a time, to permit their escape by gravity into position to be picked up by the screws. 75

4. In a typographical distributing mechanism comprising a distributor bar and a set of matrix conveying screws, the combination of a distributor box through which the matrices pass by gravity, shoulders or abutments for arresting the matrices within the box, a reciprocating finger for lifting the arrested matrices, one at a time, above said shoulders to permit their escape by gravity into position to be picked up by the screws, and inclined surfaces extending downwardly from the arresting shoulders to direct the escaping matrices to the pick-up position. 80

5. In a typographical distributing mechanism comprising a distributor bar and a set of matrix conveying screws, the combination of guide means along which the matrices pass facewise by gravity to the screws, means for arresting the matrices at a point in advance of the screws, means for releasing the arrested matrices, one at a time, to permit their escape by gravity into position to be picked up by the screws, and means for displacing the released matrices 95 facewise to facilitate their escape to the pick-up position. 100

6. In a typographical distributing mechanism comprising a distributor bar and a set of matrix conveying screws, the combination of a distributor box through which the matrices pass by gravity, shoulders or abutments for arresting the matrices within the box, a lifting finger for releasing the arrested matrices, inclined surfaces arranged to direct the released matrices into position to be picked up by the screws, and means for displacing the released matrices facewise to facilitate their escape down said inclined surfaces to the pick-up position. 110 115

7. In a typographical distributing mechanism comprising a distributor bar and a set of matrix conveying screws, the combination of a distributor box through which the matrices pass by gravity, guide rails arranged therein and formed with matrix arresting shoulders and with inclined surfaces leading downwardly therefrom, a reciprocating finger for lifting the arrested matrices successively above the shoulders to permit their escape down said inclined surfaces into position to be picked up by the screws, and means for displacing the lifted matrices facewise to allow them to descend 125 along said inclined surfaces. 130

8. In a typographical distributing mechanism comprising a distributor bar and a set of matrix conveying screws, the combination of a distributor box through which the matrices pass by gravity, means for arresting the matrices within the box, means for releasing the arrested matrices, one at a time, to permit their escape by gravity into position to be picked up by the screws, and unitary means to prevent the release of more than one matrix at a time and for displacing the released matrices facewise to facilitate their escape to the pick-up position.

9. In a typographical distributing mechanism comprising a distributor bar and a set of matrix conveying screws, the combination of a distributor box through which the matrices pass by gravity, upper and lower guide rails arranged therein and formed with matrix arresting shoulders and inclined surfaces leading downwardly therefrom, a reciprocating finger for lifting the arrested matrices successively above the shoulders to permit their escape, one at a time, into position to be picked up by the screws, and a blade arranged to cooperate with the matrices to prevent more than one being lifted at the same time, said blade being operated by the lifted matrices to displace them facewise to bring their projecting ears above said inclined surfaces down which they pass to the pick-up position.

10. A typographical distributing mechanism according to any one of the foregoing claims, characterized by the fact that the conveying screws are cut away or recessed at their receiving ends to give more room

and time for the released matrices to reach the pick-up position.

11. In a typographical distributing mechanism comprising a distributor bar and a set of matrix conveying screws, the combination of a distributor box through which the matrices pass by gravity, means for arresting the matrices within the box, means for releasing the arrested matrices, inclined surfaces arranged to direct the released matrices into position to be picked up by the screws, means for displacing the released matrices facewise to facilitate their escape down said inclined surfaces to the pick-up position, and means for restraining the matrices against abnormal facewise displacement.

12. In a typographical distributing mechanism comprising a distributor bar and a set of matrix conveying screws, the combination of a distributor box through which the matrices pass by gravity, guide rails arranged therein and having shoulders to arrest the matrices, a reciprocating finger for lifting the arrested matrices successively above the shoulders to permit their escape, one at a time, into position to be picked up by the screws, inclined surfaces extending downwardly from the arresting shoulders, and cam surfaces arranged to displace the matrices facewise as they are lifted to bring their projecting ears over said inclined surfaces.

In testimony whereof, I have affixed my signature hereto.

GEORGE P. KINGSBURY.
